UNITED STATES PATENT OFFICE.

CHARLES H. HALL, OF NEW YORK, N. Y.

IMPROVEMENT IN STEAM VACUUM-PUMPS.

Specification forming part of Letters Patent No. 131,522, dated September 24, 1872.

CASE H.

To all whom it may concern:

Be it known that I, CHARLES H. HALL, of New York city, in the State of New York, have invented a certain Improvement in Steam Pumping Apparatus, of which the following is a specification:

To distinguish this from other inventions of my own, which are somewhat analogous, I will designate this particular invention by the letter H.

The apparatus belongs to that class of steam-pumps in which the solid working parts are small, relatively, to the capacity of the apparatus, and the steam is caused to act by direct pressure upon the water. There is a marked gain by the reduction of rubbing surfaces and the great efficiency and small cost of the apparatus.

The following is a description of what I consider the best means of carrying out the invention. The accompanying drawing forms a part of this specification.

Figure 1 is a vertical section, and Fig. 2 is a plan view.

Similar letters of reference indicate like parts in all the figures.

A¹ A² are vessels of equal size, formed of cast-iron, in one piece, and adapted to resist a strong internal pressure, as also to resist the external pressure of the atmosphere when a vacuum is formed therein. E is a steam-pipe which communicates with a boiler, not represented. The steam-pipe E is of small internal diameter, or there must be at some point in the steam-connection a narrow passage through which the steam cannot flow readily except in a very contracted current. O is a pipe of sufficient size communicating with the tank or well from which the water is to be taken; and P is a delivery-pipe adapted to convey away the water under pressure and discharge it at a higher point or wherever it is desired to force the water. The chambers A¹ and A² are filled alternately with steam and water. The action is self-controlling. When the steam is excluded from a chamber the water is received from the pipe O and fills it. Meantime the opposite chamber is being emptied of its water by the steam entering at its top and pressing downward on the surface with such

force as to discharge the water outward through the discharge-pipe. When the water is thus expelled the reception of steam is cut off and the chamber is soon again filled with water. While one chamber is being filled with water the other is expelling its water. The valves e¹ e² control the admission of steam to the chambers from the steam-pipe E. The valves are mounted, as represented in the chain F, which runs over the pulleys i¹ i² above, and also is strained around the pulleys h¹ h² in the lower portion of the apparatus. The chain not only carries the valves e¹ e², but also large water-induction valves o¹ o². The discharge-valves p¹ p² are mounted in separate chambers on opposite sides of the apparatus. The water, after being delivered through the valves p¹ p², is admitted into a single discharge-pipe, P.

The action of the apparatus depends on the suddenness with which a vacuum is formed when a chamber is nearly emptied. Supposing the valve e¹ to be closed and the valve o¹ to be open, the vacuum in the chamber A¹ induces a rise of water upward through the pipe O and past the valve o¹ until the chamber A¹ is filled. It is now ready for a change in the position of all the valves by the rendering of the chain F around the several pulleys i¹ i² h¹ h², which movement will shut off the steam from the chamber A² and admit the steam to the chamber A¹. Prior to this change of position of the valves, or, in other words, while the parts are in the positions represented, the steam, flowing past the valve e² into the chamber A², forces out the water from this latter chamber, forcing it upward past the delivery-valve p². The desired movement of the chain F and the consequent change of position of all the valves is rapid and reliable when it is once initiated. It is initiated by a sudden lowering of the pressure of the steam in the chamber A², due to a sudden condensation of the steam when the water-surface is disturbed. It will be readily understood that the presence of the steam pressing upon the surface of the water in a vessel induces a heating of the immediate surface; but the hot particles at the surface do not mingle with the colder ones below. They remain, by

their superior levity, on the extreme upper surface of the water. As the water is expelled the water-surface sinks, but the particles which have become heated and lie upon its top are not much disturbed, and the condensation of steam is very slight. When, however, the sinking of the water-surface has progressed beyond a certain line, which is the upper edge of the discharge-passage O, steam commences to escape instead of the water. This would induce a flow of the steam up past the discharge-valve p^2 into the discharge-pipe P, but it never in practice escapes to any considerable extent. The moment it commences to escape it disturbs the water-surface, and, by removing the heated stratum thereon, induces such an active condensation of the steam in the entire chamber as to form a partial vacuum; and this, by the upward flow of the water through the pipe O into the chamber, acting against the valve o^2 , induces a movement of the chain F and the desired change of position of all the valves. That is to say, the large valve o^2 presents so ample a surface to the pressure of the water that it is easily lifted by the pressure of the water inward from the pipe O, and rises as high as it is allowed by the chain F. The movement of the chain, thus induced, closes the steam-valve e^2 , and also the water-valve o^1 , and opens the steam-

valve e^1 . The operations now proceed in the chambers until another change of position of the chain F, and consequently of all the valves, is induced in the same manner as has been heretofore described. The arrangement of the chain F and of the several pulleys avoids the necessity for any stuffing-box or packing. There are no tightly-rubbing surfaces, and the action of the water upon the valves o^1 o^2 forms a direct and reliable source of power to alternate the steam-valves at the proper time.

I claim as my invention—

1. The chain or flexible connection F, carrying the induction-valves o^1 o^2 , and causing them to move simultaneously, and also to operate the steam-controlling means e^1 e^2 , arranged substantially as herein specified.

2. The combination and arrangement of the chain F, valves e^1 e^2 o^1 o^2 , and pulleys i^1 i^2 h^1 h^2 so as to operate relatively to each other and to the water and steam chambers A¹ A² and the connected passages, as herein specified.

In testimony whereof I have hereunto set my hand this 18th day of May, 1872, in the presence of two subscribing witnesses.

C. H. HALL.
